ABSTRACT OF THE DISCLOSURE

A rotary brush device is provided for scrubbing the casting cavity of a graphite mold. Rotary brushes are attached to an overhead trolley, which guides the brushes through the open mold. Pivottally mounted arms actuated by power cylinders are connected to the brushes for swinging the rotating brushes out against the internal mold surfaces and retracting the brushes after the cleaning operation has been completed. A system is provided to direct a water spray against the area of the mold being cleaned.

This invention relates to mold cleaning devices and more particularly to a device for cleaning graphite molds that include opposed surfaces forming at least a portion of the casting cavity.

The Sylvester Patent No. 2,340,926 discloses an adjustable chill mold for casting steel slabs. The mold includes a wheeled chassis movable along supporting rails, with the chassis supporting two side graphite blocks, which, together with top, end and bottom blocks, define the casting cavity. Suitable means are provided for moving the side blocks apart to remove the cast slab after the pouring operation has been completed.

In the use of that type mold apparatus described above, it has been found desirable to minimize erosion of the graphite block casting surfaces and to improve surface qualities of the castings by applying certain combinations of materials, such as fine aluminum dust in a moist clay binder, to the mold surfaces defining the casting cavity. Such mixtures, called mold washes, have the beneficial effect of aiding to prevent adherence of the steel to the internal graphite surfaces.

In removing the slab from the mold, however, some of the mold wash and some slag may adhere to the internal mold surfaces, thereby necessitating removal of these adherents prior to any subsequent casting operation. If the mold is used continually, hand removal of the residual mold wash and slag is normally too time consuming and dangerous, since the temperature of the mold may be in the neighborhood of 500° F. during the time allotted for cleaning.

Accordingly, an object of this invention is to provide a mold cleaning or scrubbing device that will remove mold washes and slag from at least a portion of the cavity defining surfaces of a mold.

Another object of this invention is the provision of a mold cleaning device that is essentially automatic and self-adjusting during operation.

Other objects will become apparent to those skilled in the art from the following description and appended claims, taken in connection with the accompanying drawings wherein:

FIGURE 1 is an overall elevational view of the presently described invention;

FIGURE 2 is a top plan view of the device shown in FIGURE 1;

FIGURE 3 is a sectional elevational view taken along line 3—3 of FIGURE 1;

FIGURE 4 is a detailed side elevational view of the cleaning apparatus shown generally in FIGURE 1;

2

FIGURE 5 is a sectional view taken along line 5—5 of FIGURE 4;

FIGURE 6 is a detailed end elevational view of the cleaning apparatus shown generally in FIGURE 1;

FIGURE 7 is a plan sectional view taken along line 7—7 of FIGURE 4, showing the brush driving apparatus in greater detail; and

FIGURE 8 is a simplified schematic view illustrating the brush driving mechanism.

It will be understood that certain details have been omitted from some of the views for the sake of clarity or where those details are better illustrated in other views.

With reference now more particularly to FIGURES 1—3, the mold cleaning device is suspended from a gantry 11 comprising a pair of spaced horizontal beams 10 located above the mold, indicated generally at 12. Beams 10 are separated by a plurality of transverse support elements 14 and are supported at their ends in any convenient manner. In the embodiment shown, one end of beams 10 is supported by a pair of slightly inclined columns 16 secured at their base to a foundation frame 18 by gusset plates 20, and the other end of said beams is supported upon a transverse beam 22 secured by means of a gusset plate 24 to the framework 26 of the building. A pair of rails 28 (FIGS. 2 and 3) are secured along the underside of beams 10.

A trolley 30 is provided for moving the cleaning device along the length of the spaced beams 10 and comprises a horizontally disposed rectangular frame 32 carrying rotatable wheels 36 near the corners thereof, said wheels resting upon the aforementioned rails 28 for rolling movement of the trolley.

Means are provided for moving the trolley 30 along the rails 28, such as motor 38 secured to the trolley in driving relationship by means of a belt 40 with a shaft 42 journaled in said trolley, and a pinion gear 46 secured to each end of said shaft engaging toothed racks 48 (FIG. 3) secured along the spaced horizontal beams 10.

Trolley 30 also comprises a downwardly extending box framework 31 that includes four spaced vertical channel members 50 secured to the trolley rectangular frame 32 and interconnected by a plurality of braces 52. The downwardly extending box framework 31 carries the rotatable cleaning brushes 54 and 55 as hereinafter described.

As best shown in FIGURES 3, 4 and 6, a motor 56 is secured to box framework 31 and is connected in a driving relationship by belts 58 to a pulley 59 driving a shaft 60 journaled within a plurality of bearings 62 secured to said framework. Shaft 60 is connected by a spacer coupling 64 to a gear box 66 to rotate two or more pulleys therefrom. In the present embodiment, as best shown in FIGURES 3—6, two pulleys 68 are provided at the top of gear box 66, one of which may be directly driven by shaft 60.

As best shown in FIGURES 3—7, two main cylindrical brushes 54 are mounted vertically on box framework 31, said brushes each being secured to a shaft 70 journaled at both ends in bearings 72. Bearings 72 are held at the respective ends of a bracket 74 extending around the brushes 54 to form a unitary assembly with the brushes rotatable therein. Each bracket 74 is secured to one end of one or more L-shaped arms 76 (FIGS. 5, 7 and 8), the other ends of said arms being pivotally mounted by bearings 78 on the box framework 31.

A pulley 80 is secured at the upper end of each brush shaft 70 and is operatively connected by a belt 82 to a respective gear box pulley 68. Spring tensioned idler pulleys 84 may be provided on box framework 31 to engage the belts 82, in order to keep the drive system under proper operating tension. The trolley motor 38 and the brush motor 56 are powered by flexible cable means 86

(FIGS. 1-3) connected to the upper spaced horizontal beams 10.

As mentioned above, the L-shaped arms 76 carrying the brush assembly are pivotally connected to the box framework and may thus swing the rotating brushes 54 out against the area of the mold to be cleaned. Means are provided to actuate each of the arms 76 and may comprise a double acting pneumatic cylinder 88 as shown in FIGURE 7, said cylinder being pivotally connected between the box framework 31 and an arm 76.

As best illustrated in FIGURES 4, 5 and 8, the arms 76 are mounted at pivot points that are substantially coaxial with their corresponding gear box pulleys 68. This arrangement allows the arms 76 to swing out without altering the tension on the belts 82.

As shown in FIGURE 4, a water spray system may be provided, comprising vertical lines 90 connected to a regulated source of supply by any convenient means. A plurality of directional spray heads 92 are provided along lines 90 in a spaced relationship, in order to provide a spray over the entire vertical portion of the mold being scrubbed. The spray system has been found effective to greatly minimize the dust that would otherwise be created during the scrubbing operation. Preferably, as shown in FIGURE 4, a spray line is provided at both sides of each brush 54. A shut-off valve 94 may be provided at the top of each line 90 to facilitate repair should malfunctioning occur.

In addition to the main brushes 54, two auxiliary brushes 55 may be provided to accommodate molds of greater heights. In this instance, the auxiliary brushes 55 are mounted on bearings 96 and connected to a pulley 98 driven by a belt 100 and pulley 102 from the underside of the gear box 66. The bearings 96 are connected to one end of a pivotally mounted arm 104 (FIGS. 5 and 7) actuated by double acting power means 106, similarly to that arrangement hereinbefore described.

In operation, the open mold 12 is positioned under the framework of the cleaning device such that the center of the cavity and the centerline of the box framework 31 approximately coincide, as shown in FIGURE 3. It will be understood that the mold 12 comprises a pair of opposed side blocks 108 having planar internal surfaces, which, together with a top block 110, bottom block 112 and end block and ingate (not shown) define the casting cavity. Means are provided to move the side blocks 108 apart, and the mold shown in FIGURE 3 is shown in an open position. It should be understood that the internal surfaces of the side blocks 108 need not be planar, and the outer contour of the brushes may be designed to accommodate other continuous mold surfaces.

After positioning, power is supplied to the trolley motor 38 and the brush motor 56, and the trolley 30 proceeds down the rails 28 on its wheels 36 with the brushes 54 spinning. Water is also supplied to spray lines 90.

Upon entering the mold, pneumatic cylinders 88 are extended, thereby causing the brushes 54 to engage the planar surfaces of the side blocks 108, as best understood by viewing FIGURES 3 and 8. Suitable means are provided to reverse the trolley 30 whereby the cleaning device may reciprocate for as many cycles necessary to clean the mold. A reasonable trolley speed has been found to be in the neighborhood of 60 feet per minute, and about eight or ten passes (four or five complete cycles) are usually sufficient to clean the mold. The clean mold may then be moved from under the cleaning device for subsequent coating and casting.

It has been discovered that the speed of rotation of the brushes and the material from which the brushes are constructed are important factors in the successful use of the presently described apparatus. Very high rotative speeds cause excessive wear on either or both of the brush bristles and the graphite surfaces. Relatively hard bristles, such as steel wire, score the graphite, while relatively soft bristles, such as straw, wear out too rapidly. It has been

found that cylindrical, medium dense, tufted brushes of 14 inch diameter, composed of .004 inch diameter brass bristles having dulled ends and revolved at about 400 r.p.m. with the trolley moving at about 24 feet per minute, produce very good results. A loose canvas buffering wheel operated at about 400 r.p.m. with $\frac{1}{4}$ to $\frac{1}{2}$ in. deflection has also been found to be effective.

Nylon brushes have also been used successfully in conjunction with means to cool the brushes. For this purpose, a water supply may be connected to each brush shaft 70 and orifices 112 (FIG. 7) may be provided along the length thereof for cooling the revolving brushes.

Obviously, other types and sizes of brushes may be used if different operating parameters are utilized in the device. It is also obvious that further modifications may be made to the present invention without departing from the spirit or scope of the appended claims.

Having thus described the invention, what is claimed is:

1. Cleaning apparatus for a mold wherein the mold includes two opposed vertical surfaces, comprising a trolley movable above said mold surfaces, a framework suspended from said trolley, at least one pair of arms pivotally mounted on said framework, means for swinging said arms outwardly and inwardly from said framework, brush means corresponding to said vertical surfaces and operatively connected to said arms, and means for rotating said brush means.

2. The invention according to claim 1 wherein a pair of spaced rails is supported above said mold, wheels are mounted on said trolley for traveling on said rails, and means are provided for urging said trolley along said rails.

3. The invention according to claim 1 wherein water spray means is provided in conjunction with said brush means, said water spray means including at least one line disposed vertically from said framework, a plurality of spray heads arranged along said line, and means for supplying water to said line.

4. The invention according to claim 1 wherein said means for rotating said brush means comprises a shaft rotatably mounted in said framework, means for rotating said shaft, gear means associated with said shaft for rotating at least two pulleys, other pulleys connected to each of said brush means, and belt means for connecting said two pulleys to corresponding other pulleys.

5. The invention according to claim 4 wherein each of said pulleys rotated by said gear means corresponds to one of said arms pivotally mounted on said framework and wherein the pivot axis of said arms is substantially coaxial with the pivot axis of corresponding pulleys rotated by said gear means.

6. The invention according to claim 5 wherein the opposed vertical surfaces of said mold are substantially planar, and said brush means are substantially cylindrical in shape.

7. The invention according to claim 6 wherein said brush means comprises 0.004 inch diameter brass bristles having dulled ends.

8. The invention according to claim 6 wherein said brush means comprises a loose canvas buffering wheel.

9. The invention according to claim 6 wherein said brush means comprises nylon bristles, and means are provided for cooling said bristles during the operation thereof.
